UNITED STATES PATENT OFFICE.

ALFRED TROSCH, OF ROCHESTER, NEW YORK, ASSIGNOR TO CONSOLIDATED MACHINE TOOL CORPORATION OF AMERICA, OF ROCHESTER, NEW YORK, A CORPORATION OF DELAWARE.

CROSS-RAIL CLAMPING MECHANISM FOR MACHINE TOOLS.

Application filed May 4, 1925. Serial No. 27,790.

My invention relates to cross-rail clamping means for machine tools such as planers, boring mills, planer type milling machines, and the like, and has for its purpose to afford mechanism that can be quickly and readily operated either to clamp or release the cross-rail to the uprights.

Another object of the invention is to afford a clamping mechanism of simple construction, that functions to clamp the cross-rail to both edges of the uprights and to hold the cross-rail at its adjusted position with maximum rigidity and stiffness.

A further purpose of my improvement is to afford a form and arrangement of clamping member that lends itself readily to the simultaneous control of a multiplicity of clamping units, and which permits efficiently clamping to both the inner and outer edges of the uprights.

To these ends, the invention comprises the construction that will appear clearly from the following description when read in conjunction with the accompanying drawings, the novel features being pointed out in the claims following the specification.

In the drawings:

Figure 1 is a perspective view of a planer showing my invention applied thereto;

Figure 2 is a plan view;

Figure 3 is an enlarged view partially broken away and in section;

Figure 4 is a vertical sectional view on line 4-4 of Figure 3, and

Figure 5 is a perspective view of one of the clamping members.

Referring more particularly to the drawings, in which like reference numerals refer to the same parts, 1 designates the cross-rail of a planer including uprights 2 to which the cross-rail is clamped after adjustment to proper position. In order to effect rigid clamping onto the uprights, so that the cross-rail may be held firmly in position, I provide means for clamping to both the inner and outer edges of each upright, the details of which I will now describe.

Referring to Figure 3, 3 designates the inner edge of one of the uprights while 4 is the outer edge of the same, each edge being gripped by a clamping member that is of the same general construction. Each clamping member is preferably of elongated construction and comprises an upright-en-

gaging or clamping portion or edge 5 and a central portion 6 having openings 7 that engage posts 8 fixed to the cross-rail. The posts 8 support the clamping member on the cross-rail, and the openings 7 are made slightly larger than the posts 8 to permit a slight play or tilting of the clamping member upon the posts 8 about a vertical axis. This tilting motion is determined by stop means preferably in the form of nuts 9 at the outer ends of the posts 8. The nuts 9 are adjustable and after being placed in proper position, serve as abutments against which the clamping member rocks to grip the upright. On the other side of the central portion 6, the clamping member includes an inclined surface 10 which is engaged by a tapered or wedge actuator 11 to effect the necessary tilting movement just referred to. The wedge actuator 11 is moved upwardly or downwardly by a threaded post 12 which has fixed to its upper end a worm gear 13 operated by a worm 14 on the operating shaft 15.

There is a clamping unit such as just described for both edges of each upright, and there is an operating worm for each clamping unit, all of the operating worms being fixed upon the common operating shaft 15 which has a squared end 16 upon which an operating handle is positionable for turning when it is desired to effect clamping or releasing of the cross-rail upon the uprights.

The invention affords an extremely practical and effective clamping mechanism that can be controlled with great facility and certainty, and the structure described may be changed in detail without departing from the fundamental features or character of my improvements. This application is intended to cover any modifications or departures coming within the intent of the invention or the scope of the following claims.

I claim:

1. The combination with the uprights and cross-rail of a machine tool such as a planer, of means for clamping the cross-rail to the uprights including clamping members for both the inner and outer edges of each upright, and means for simultaneously operating the several clamping members.

2. The combination with the uprights and cross-rail of a machine tool such as a planer, of means for clamping the cross-rail to the

uprights including clamping members for both the inner and outer edges of each upright, and means controllable from one end of the cross-rail for simultaneously operating the several clamping members.

3. The combination with the uprights and cross-rail of a machine tool such as a planer, of means for clamping the cross-rail to the uprights including clamping members for both the inner and outer edges of each upright, and means for simultaneously actuating the several clamping members, said actuating means extending along the cross-rail beyond both uprights and operable from one end of the cross-rail.

4. The combination with the uprights and cross-rail of a machine tool such as a planer, of means for clamping the cross-rail to the uprights including clamping members for both the inner and outer edges of each upright, and means for simultaneously actuating the several clamping members, said actuating means consisting of a shaft located on top of the cross-rail and extending from one end thereof to the other, said shaft being operable from one end of the cross-rail.

5. The combination with the uprights and cross-rail of a machine tool such as a planer, of means for clamping the cross-rail to the uprights including a tiltable clamping member for each of the inner and outer edges of the uprights, a vertically movable wedge actuator for each clamping member, a vertically arranged screw for elevating or lowering each wedge actuator, and means carried by the cross-rail for simultaneously operating said screws, said operating means extending along the cross-rail beyond both uprights and operable from one end of the cross-rail.

6. The combination with the uprights and cross-rail of a machine tool such as a planer, of means for clamping the cross-rail to the uprights including a tiltable clamping member for each of the inner and outer edges of the uprights, a vertically movable wedge actuator for each clamping member, a vertically arranged screw for elevating or lower-

ing each wedge actuator, and means for simultaneously operating the several screws. 50

7. The combination with the uprights and cross-rail of a machine tool such as a planer, of means for clamping the cross-rail to the uprights comprising a tiltable clamping member cooperating with an upright, a vertically movable wedge actuator for the clamping member, a vertically arranged screw for elevating or lowering the wedge actuator, a worm wheel fixed to the screw, and means for operating the worm wheel. 55

8. The combination with the uprights and cross-rail of a machine tool such as a planer, of means for clamping the cross-rail to the uprights comprising tiltable clamping members cooperating with both the inner and outer edges of each upright, a vertically movable wedge actuator for each clamping member, a vertically arranged screw for elevating or lowering each wedge actuator, a worm wheel fixed to each screw, and a worm 60 shaft carrying a series of worms for simultaneously operating the several worm wheels to effect engagement of the clamping members with said inner and outer edges of the uprights, said worm shaft extending along 70 the cross-rail beyond both uprights and operable from one end of the cross-rail. 75

9. The combination with the uprights and cross-rail of a machine tool such as a planer, of means for clamping the cross-rail to the 80 uprights comprising clamping members cooperating with both the inner and outer edges of each upright, each clamping member being tiltable about a vertical axis for engaging with an upright, a vertically movable wedge actuator for each clamping member, and means extending along the cross-rail beyond both uprights and operable from one end of the cross-rail for simultaneously elevating or lowering all of said 85 wedge actuators to effect engagement or disengagement with said inner and outer edges of the uprights.

In witness whereof, I have hereunto signed my name.

ALFRED TROSCH.
